UNITED STATES PATENT OFFICE.

ANDRÉ CHÉRON-DUVAL, OF HOLLYWOOD, CALIFORNIA.

DESIGN FOR AN ORNAMENT FOR RADIATOR CAPS.

Application filed October 21, 1926. Serial No. 19,440. Term of patent 7 years.

To all whom it may concern:

Be it known that I, ANDRÉ CHÉRON-DUVAL, a citizen of the Republic of France, residing at Hollywood, in the county of Los Angeles and State of California, have invented a new, original, and ornamental Design for Ornament for Radiator Caps, of which the following is a specification, reference being had to the accompanying drawing, forming part thereof.

In the drawings:

Figure 1 is a plan view of an ornament for radiator caps, showing my new design; and

Figure 2 is a view in side elevation of an ornament for radiator caps, showing my new design.

I claim:

The ornamental design for an ornament for radiator caps, as shown.

ANDRÉ CHÉRON-DUVAL.
